DESIGN FOR A JEWELRY DISPLAY BOX OR SIMILAR ARTICLE

Rudolf Christen, Buffalo, N. Y.

Application July 9, 1937, Serial No. 70,322

Term of patent 3½ years

To all whom it may concern:

Be it known that I, Rudolf Christen, a citizen of the United States, residing at Buffalo, Erie county, State of New York, have invented a new, original, and ornamental Design for a Jewelry Display Box, or similar article, of which the following is a specification, reference being had to the accompanying drawing, forming a part thereof.

In the drawing:

Fig. 1 is a front perspective view of the jewelry display box, showing my new design in open display position;

Fig. 2 is a front perspective view thereof, in reversed closed position; and

Fig. 3 is a cross-sectional view, on a reduced scale taken along line 3—3 of Fig. 1.

The jewelry display box of this design consists of a container element having a closure for its open face which is reversible on the container at will in order to present either face outwardly.

I claim:

The ornamental design for a jewelry display box or similar article substantially as shown and described.

RUDOLF CHRISTEN.
